HOLDER FOR STREET RAILWAY TRANSFERS AND THE LIKE

Filed April 12, 1934

UNITED STATES PATENT OFFICE

1,968,717

HOLDER FOR STREET RAILWAY TRANS-FERS AND THE LIKE

Ira C. Smith, Washington, D. C.

Application April 12, 1934, Serial No. 720,341

7 Claims. (Cl. 206—40.5)

My invention relates to holders for street railway transfers and the like, which contain time indicia, and its principal object is to provide the holder with means which may be disposed in different positions of adjustment, so that transfers may be torn from the holder in varying shapes, the particular shape of the transfer having reference to the time at which the transfer expires. The holder is particularly suitable for transfers having figures representing hours and minutes arranged in laterally spaced columns, the figures in the minute column being arranged in groups, each group preferably containing identical figures and being common to a plurality of figures in the hour column.

A primary feature of the invention consists in providing the holder with a base member and in rotatably mounting thereon means having a portion spaced outwardly from the base adapted to overlap the outer face of the transfers, the outwardly spaced portion having a transfer tearing edge which may be rotated into different angular positions of adjustment with respect to the base member, so that transfers of varying shapes may be torn from the holder.

Another feature of the invention consists in providing the base member of the holder with a plate spring extending longitudinally thereof, which is adapted to maintain the transfers in engagement with the rotatable member of the holder formed with the transfer tearing edge.

Other and more specific features of the invention, residing in advantageous forms, combinations and relations of parts, will hereinafter appear and be pointed out in the claims. In the drawing, illustrating different embodiments of the invention,

Figure 1 is a perspective view of the holder, with the transfers in place.

Figure 2 is a side view of the holder, with parts broken away.

Figure 3 is a longitudinal sectional view of the holder taken on line 3—3 of Figure 2.

Figure 4 is a perspective view of the holder, with portions of the spring plates broken away.

Figures 5 and 6 are views of the holder and transfers, showing the rotatable element of the holder in different positions of angular adjustment.

Figure 7 is a side elevation of a modified form of the invention, illustrating a holder for receiving two bundles of transfers side by side.

Figure 8 is a longitudinal sectional view taken on line 8—8 of Figure 7.

Referring more particularly to the drawing and

especially to Figures 1 to 6, inclusive, 1 indicates the base member of the holder, which is preferably formed of an elongated piece of flat metal of any suitable shape or size depending upon the transfers it is intended to receive. Rotatably mounted on the base member, adjacent one end thereof, is a loop member 2 having spaced inner and outer portions 3 and 4, respectively. This member may be conveniently formed from a strip of metal, which can be readily bent into the form of a loop and its free ends may be connected in any suitable manner. As illustrated in the drawing, the means connecting the free ends of the loop may be a rivet 5 and, by extending the rivet through the base member, it may conveniently serve to rotatably connect the loop to the base.

In the form of the invention illustrated in Figures 1 to 6, inclusive, each side of the base member is provided with a loop member 2, so that the holder may receive two bundles of transfers back to back. As the parts of the holder on one side of the base are duplicates of the parts of the holder on the opposite side thereof, corresponding parts are indicated by the same reference numerals and, in the main, the holder will be described as though it were formed to receive only one bundle of transfers.

The inner and outer portions of the loop 2 are disposed on the same side of the base member and the outer portion is spaced sufficiently therefrom to overlap the outer face of a bundle of transfers. Extending longitudinally of the base member is a plate spring 6, which projects on opposite sides of the loop member intermediate the inner and outer portions thereof. On one side of the loop member, the plate spring is rigidly secured to the base by suitable means, such as rivets 7, and, on the opposite side thereof, it is spaced from the base and normally tends to engage the inner face of the outer portion 4 of the loop. The bundle of transfers is adapted to be received by the holder between the outer portion of the loop and the plate spring and the latter, due to its inherent tendency to engage the outer portion, will maintain the transfers in engagement therewith.

As the spring 6 tends to force the loop member outwardly away from the base member and thereby bend the inner portion of the loop adjacent the rivet 5, the base member is provided with means adapted to overlap the inner faces of the inner portion 3 on opposite sides of the rivet 5 and preferably adjacent the side edges of the base. This means may advantageously comprise metallic straps 9, which are rigidly secured

to the base by rivets 10. Not only do these straps serve to prevent distortion of the loop by the spring 6, but they also serve to provide surfaces which are frictionally engaged by the loop, where-
5 by the loop will be frictionally held in a desired position of adjustment. The frictional forces acting between the loop and the straps 9 are, of course, produced by the spring 6, which maintains these parts in engagement at all times.

- 10 One edge of the outer portion 4 of the loop member, preferably the edge adjacent the main body portion of the transfer, which is designated by the reference numeral 8, constitutes a transfer tearing edge. As the spring 6 maintains the transfers in engagement with the outer portion 4 and, therefore, also the tearing edge 8, it will be perceived that the lower portion of the transfer will be so firmly held that the body portion may be readily torn from the holder. The sides
15 11 of the loop member are spaced sufficiently from the sides of the transfers, which the holder is designed to receive, so that the loop may be rotated to present the tearing edge 8 in different positions, in order that the transfers may be torn 20 from the holder in varying shapes.

In the transfer chosen for the purpose of illustrating the invention, the figures representing hours are disposed in a column along one side of the transfer, while the figures representing minutes are disposed in a column along the other side. The hour figures, 1 to 12, inclusive, are arranged in groups and opposite each group is a set of figures indicating minutes. Thus, for example, the hour figures may be arranged in four groups, three to a group, and the figures representing minutes are arranged in a similar number of groups, each group or set of minute figures being the same.

- 30 In the operation of the device, the bundle of transfers is adapted to be slid along the base member until the desired group of hour figures is adjacent the loop member. If, for example, it is desired to issue a transfer which will expire at four thirty o'clock, the loop member will be ad-
40 justed into the position illustrated in Figure 5, or, if it be desired to issue a transfer which will expire at six o'clock, the loop member will be rotated into the position indicated in Figure 6. It will be apparent that the loop may be rotated into
45 positions intermediate the two positions indicated in Figures 5 and 6, so that transfers may be issued which will expire between four o'clock and six thirty o'clock without shifting the bundle of transfers along the holder to any material extent.
50 55 To issue transfers expiring between seven o'clock and nine thirty o'clock or between the hours contained in any of the other groups of figures, it will, of course, be necessary to shift the bundle of transfers to bring the desired group of figures adjacent the loop.

60 As explained above and as shown in the drawing in Figures 1 to 6, inclusive, it is preferred to form the holder so that it can receive transfers on both sides of the base member. When the holder is formed in this fashion, a single rivet 5 can be used for connecting the free ends of both loop members and for rotatably connecting them to the base. Moreover, the same rivets, which are employed to connect the spring 6 and the straps 9 to the base on one side of the holder, can be used for connecting the same parts to the other side of the holder.

70 75 In the modified form of the invention illustrated in Figures 7 and 8, there is shown a holder for receiving two bundles of transfers side by

side, instead of back to back. This holder comprises a base member 12 provided with two loop members 13 and two plate springs 14. Instead of mounting the loop members on the base in the manner disclosed in the preferred form of the invention, that is, by having the inner and outer portions thereof disposed on the same side of the base, they are preferably mounted so that the inner and outer portions 15 and 16 thereof overlap opposite sides of the base. For this purpose, the base 12 is provided with a slot 17 for receiving the inner side portions of each loop member. With the exception of the particular manner in which the loop member is associated with the base, all parts of the holder illustrated in the modified form of the invention are assembled and cooperate with each other in the same manner as in the preferred form of the invention.

80 85 90 95 By mounting the loop members 13, so that they overlap opposite sides of the base 12, it is unnecessary to provide the holder with strips corresponding to those designated by the reference numeral 9. The spring, although it exerts the same outward force on the loop, will not 100 tend to distort it, as the inner face of the inner portion 15 of the loop is in engagement with the rear face of the base and, since the spring will always act to maintain these parts in engagement, frictional forces are set up between the 105 loop and base sufficient to maintain the loop in a desired position of adjustment.

96 100 105 110 From the foregoing, it will be appreciated that my invention is not limited in its use to transfers of the character indicated in the drawing. Moreover, those skilled in the art will realize that the holder is not limited for use in connection with transfers, but may be used in connection with the other articles having suitable indicia, such, for example, as checks or tickets which are sometimes issued in restaurants, containing columns of suitably arranged figures.

115 What I claim is:

120 125 130 135 140 145 150 155 160 165 170 175 180 185 190 195 1 1. A holder for street railway transfers and the like involving a base member, means rotatably connected to said base member having a plate-like portion spaced outwardly therefrom adapted to overlap the outer face of the transfers, and resilient means interposed between said base member and plate portion for maintaining the transfers in engagement with the latter, said plate portion having a transfer tearing edge and said means being rotatable to permit said edge to assume different angular positions of adjustment with respect to the base member so that transfers of varying shapes may be torn from the holder.

2. A holder for street railway transfers and the like involving a base member, resilient means secured to the base member and extending longitudinally thereof, and rotatable means carried by said base member having a plate portion overlapping the outer face of said resilient means, said resilient means being adapted to hold the transfers against the inner face of said plate portion and said plate portion having a transfer tearing edge whereby transfers of varying shapes may be torn from the holder upon movement of said rotatable means into different positions of adjustment.

3. A holder for street railway transfers and the like involving an elongated base member, means rotatably connected to said base member having a plate-like portion spaced outwardly therefrom adapted to overlap the outer face of the transfers, and a plate spring member extend-

ing longitudinally of the base member adapted to maintain the transfers in engagement with said outwardly spaced plate portion, one end of said spring being rigidly secured to the base member and the other end thereof extending between said plate portion and base member, said plate portion having a transfer tearing edge and said means being rotatable to permit said edge to assume different angular positions of adjustment with respect to the base member so that transfers of varying shapes may be torn from the holder.

4. A holder for street railway transfers and the like involving a base member, means rotatably connected to said base member having a portion spaced outwardly therefrom adapted to overlap the outer face of the transfers, and a plate spring extending longitudinally of the base on opposite sides of said outwardly spaced portion adapted to maintain the transfers in engagement with the latter, said spring being rigidly secured to the base on one side of said portion and being normally spaced from the base on the other side of said portion, said portion having a transfer tearing edge and said means being rotatable to permit said edge to assume different angular positions of adjustment with respect to the base member so that transfers of varying shapes may be torn from the holder.

5. A holder for street railway transfers and the like involving a base member, a loop member rotatably mounted on said base having portions overlapping the opposite sides thereof, one of said portions having a transfer tearing edge and being spaced outwardly from the base so as to overlap the outer face of the transfers, and a plate spring extending longitudinally of the base adapted to maintain the transfers in engagement with said last named portion, said loop member being rotatable to permit said tearing edge to assume different angular positions of adjustment

with respect to the base so that transfers of varying shapes may be torn from the holder.

6. A holder for street railway transfers and the like involving a base member, a loop member rotatably mounted on the base having spaced inner and outer portions disposed on the same side of the base, said inner portion being pivotally secured to the base and said outer portion being spaced outwardly therefrom so as to overlap the outer face of the transfers, means rigid with the base overlappingly engaging the inner face of said inner portion at one side of the pivotal axis thereof, and resilient means for maintaining the transfers in engagement with said outer portion, said outer portion having a transfer tearing edge and said loop member being rotatable to permit said edge to assume different angular positions of adjustment with respect to the base member so that transfers of varying shapes may be torn from the holder.

7. A holder for street railway transfers and the like involving an elongated base member, a loop member rotatably mounted on the base having spaced inner and outer portions disposed on the same side of the base, said inner portion being pivotally secured to the base and said outer portion being spaced outwardly therefrom so as to overlap the outer face of the transfers, members rigid with the base overlappingly engaging the inner face of said inner portion on opposite sides of the pivotal axis thereof, and a plate spring extending longitudinally of the base member adapted to maintain the transfers in engagement with said outer portion, said outer portion having a transfer tearing edge and said loop being rotatable to permit said edge to assume angular positions of adjustment with respect to the base member so that transfers of varying shapes may be torn from the holder.
